TOY BELL

Leslie W. Hubbell, Cheshire, Conn., assignor to The Ball & Socket Manufacturing Company, West Cheshire, Conn., a corporation of Connecticut

Application October 16, 1952, Serial No. 315,145

5 Claims. (Cl. 116—150)

This invention relates to toy bells, generally known as novelty bells, which may assume different designs and outlines simulating the shapes of the Liberty Bell, cow bells, and other forms.

It is the object of the present invention to provide a toy bell construction which is economical to fabricate and assemble and which remains in assembled condition despite repeated handling and hard usage.

It is another object of the invention to provide a bell composed of three component parts, namely, a housing, a clapper or sounder, and a unitary support for the clapper and bell housing, each of which component parts may be stamped and fabricated at low cost. These component parts may be assembled quickly and with certainty and with no requirement for skilled manual dexterity on the part of the operator.

The invention proceeds upon the principle of stamping a bell housing with a sufficiently large opening at the head end thereof to permit the free passage of the clapper and support therefor in assembled condition from the top or outside of the bell housing to the interior thereof. The support for the bell housing and clapper is a unitary element comprising a pair of resilient arms, one of which terminates in a hook for supporting the clapper, and between which is formed the bell housing supporting loop. Following the introduction of the clapper into the housing through the head end thereof, the arms of the clapper support span the opening, and are snapped onto the bell housing, leaving the bell housing support extending above the top of the housing. Preferably seating shoulders are provided on the resilient arms of the unitary support to engage the top surface of the bell to enforce a limited and fixed entry of the support into the bell housing. This mode of assembly enables the connection of the clapper support with the eye of the clapper to be executed in the open, without pliers, and outside of the confining space within the bell housing, whereat such connections had been performed heretofore with pliers in the assembly of the clapper with the wire supporting element. This operation was time consuming and required skilled operators with a high degree of manual dexterity.

Other objects and purposes will appear from the detailed description of the invention, following hereinafter, taken in conjunction with the accompanying drawings, wherein

Fig. 1 is a front elevation of one embodiment of the bell in accordance with the present invention;

Fig. 2 is a plan view of Fig. 1;

Fig. 3 is a vertical sectional view along line 3—3 of Fig. 2;

Fig. 4 is a vertical sectional view along line 4—4 of Fig. 2;

Fig. 5 shows the bell illustrated in the above figures as the same is being assembled to bring it into its final positioning shown in Fig. 3;

Fig. 6 is a sectional view of a different embodiment of the invention and illustrates a cow bell form of housing and a dipper-shaped clapper;

Fig. 7 is a vertical sectional view of a different modification of the bell utilizing a spring wire support;

Fig. 8 is a vertical sectional view along line 8—8 of Fig. 7;

Fig. 9 illustrates an intermediate stage in the assembly of the bell shown in Figs. 7 and 8;

Fig. 10 is a horizontal sectional view along line 10—10 of Fig. 9;

2

Fig. 11 illustrates a different embodiment of the bell shown in Figs. 7 to 9 in which the housing is of cow bell design but in which the clapper and wire support therefore are similar to the wire support shown in Figs. 7 to 10;

Fig. 12 illustrates a modified form of housing and slightly modified form of wire support from that shown in Figs. 7 to 10;

Fig. 13 is an enlarged view of another embodiment of a sheet metal bell and clapper support; and

Fig. 14 is a vertical sectional view along line 14—14 of Fig. 13.

In the drawings is shown a bell housing 1 which is preferably drawn from sheet metal into an outline generally simulating the Liberty Bell. In the course of the stamping and drawing operation an opening 3 is formed in the head end 2 of the bell. With the bell housing and clapper support shown in the embodiment illustrated in Figs. 1 to 6 formed of sheet metal, the opening 3 is preferably of rectangular outline.

The clapper or sounder for the bell may be formed in any desired manner and in the embodiment shown in Figs. 1 to 5, the clapper is formed of a body 4 stamped from plane sheet metal having a supporting eye 5 at one end thereof and an enlarged portion 6 at the opposite end thereof which operates as the sounder for the bell. The eye 5 is preferably completely closed in order to maintain more certainly the connection between the clapper and the support therefor.

The support 10 is formed of sheet metal and is provided with opposed resilient arms 11 and 12 and a bell supporting loop 15 therebetween. The arm 12 of the support terminates in forked bifurcations 16 and 16' at the opposite sides of an opening 18. The terminals of these bifurcations extend inwardly and are notched at 17, 17', respectively, to provide a fulcrum of small dimension for the eye 5 of the clapper which is adapted to be introduced into the opening 18 following which the opening is closed by the realignment of lateral arms 16 and 16'.

In addition to the resilient arms 11 and 12, the bell supporting loop 15, therebetween, and the hook formed on the arm 12 for supporting the clapper 4, shoulders 13 and 14 are formed on the arms 11 and 12, respectively, by indentations in these arms in order to provide positive rests for the support on the top of the bell housing.

Thus, to assemble the three component parts of the bell, the clapper is first connected with the support by bending the bifurcations 16, 16' out of alignment in order to introduce the eye 5 of the clapper into one of them, following which the bifurcations are bent into alignment to retain the clapper onto the arm 12. This operation is one that can be rapidly executed by an inexperienced operator. Thereafter, the assembled unit of the clapper 4 and its support 10 is introduced into the bell housing from the head end or top thereof, as shown in Fig. 3, and the resilient arms of the support 11 and 12 are yieldingly guided by the edges of the rectangular opening 3 in the bell housing until the indentations in the arms 11 and 12 snap into the opposite ends of the opening at which time shoulders 13 and 14 rest upon the top of the housing, as shown in Fig. 3. These shoulders limit the travel of the support and clapper into the bell housing and assure a uniform final product.

The interconnection of the clapper with the support therefor prior to the assembly of these elements with the bell housing, enables a rapidity of assembly never attained heretofore when it was necessary to first integrate the support with the bell and then integrate the clapper with the support in the confining space within the bell housing. This is particularly true in the manufacture of toy bells of small size.

In Fig. 6 is shown a different embodiment of the invention in which the housing 1a is of a cow-bell design and in which the clapper instead of assuming a plane sheet metal form is formed of a stamped and drawn unit consisting of a shank 7 having the completely closed supporting eye 8 at one end thereof and a dipper-shaped sounding element 9 at the opposite end thereof. As described above, the eye 8 of the clapper is engaged with

arm 12 prior to the introduction of the combined assembly into the bell housing through the top thereof.

Figs. 7 to 10 illustrate a third embodiment of the invention utilizing a bell housing in the outline of a Liberty Bell. In this embodiment a resilient wire support is used rather than a sheet metal support. This support 20 is formed with opposite resilient arms 21 and 22 with the bell supporting loop 20' medially thereof. One of the arms 21 terminates in a hook 25 for receiving the eye 5 of the clapper. The opposite arm 22 terminates in a projection 26 in intersecting relation with hook 25 and adjacent thereto in order to prevent the disengagement of the clapper from the hook 25 following its assembly.

Indentations are formed in the opposite arms 21 and 22 in order to provide shoulders 23 and 24 thereabove, which seat upon the top of the bell at the ends of the opening provided in the head end of the bell. This opening is clearly shown in Fig. 10 and is composed of a main circular area 30 having constricted extensions 31 upon the opposite sides thereof. These extensions permit the free passage of the enlarged portion 6 of the clapper into the bell housing. At the same time, they serve a useful purpose in providing rests for the shoulders 23 and 24 which are conveniently accommodated in these constrictions 31.

The bell illustrated in this embodiment may be assembled conveniently, as indicated in Figs. 9 and 10, by the dropping of the clapper 4 with the wire support interconnected therewith through the opening 31. Following the introduction of the widest portion of the clapper assembly into the interior of the housing, the assembly may be turned 90° around a vertical axis in order to enable the resilient arms 21 and 22 to snap into the constrictions 31 of the opening immediately below the shoulders 23 and 24 provided in the resilient arms, as shown in Figs. 7 and 8. The shoulders 23 and 24 limit the amount of drop of the clapper into the bell housing.

In lieu of the clapper 4 shown in Figs. 7 to 10, a clapper of the type shown in Fig. 6 may be used in the assembly of the bell, in which case the circular opening 30 would permit the passage therethrough of the largest portion 9 of the clapper.

Fig. 11 shows a cow-bell housing 1b combined with a plane sheet metal clapper 4 of the type shown in Figs. 1 to 5 and 7 to 10. The opening in this bell housing may assume the form shown in Fig. 10 and the mode of assembly of the three component elements is the same as described above.

Fig. 12 shows a different embodiment of the invention, utilizing a bell housing 1c of still another design which is provided in the head end thereof with openings 30, 31, as shown in Fig. 10. In this case the resilient arm 22 of the support is brought into juxtaposition with the hook 25 for supporting the clapper rather than in intersecting relationship, as shown in Figs. 7 to 11.

Of course, clappers of the type shown in Fig. 6 may be utilized with the housings illustrated in Figs. 11 and 12.

Figs. 13 and 14 illustrate still another form of sheet metal bell and clapper support presenting a variation of the support shown in Fig. 4. In this embodiment a strap of sheet metal 40 is shaped to form a supporting loop 41 at the midportion thereof between the two resilient arms 42 and 43 which tend to press towards each other. Shoulders 44 and 45 are formed at the lower limits of the loop support for snapping into resilient engagement with the ends of the rectangular opening 3 in the head end 2 of the bell.

An inclined slot 46 extends from an edge of arm 42 and terminates in circular opening 47 at the end of the arm. The eye 8 of the clapper 7 is adapted to be threaded onto the free end of arm 42 by passing through the slot 46 while arm 43 is flexed away from arm 42. When arm 43 is permitted to return to its position of abutment with arm 42 adjacent to slot 46, the clapper is secured against loss or unintentional removal from arm 42, since the completely closed eye 8 of the clapper is blocked from movement along slot 46.

While I have described my invention as embodied in a specific form and as operating in a specific manner for purposes of illustration, it should be understood that I do not limit my invention thereto, since various modifications will suggest themselves to those skilled in the art, without departing from the spirit of my invention, the scope of which is set forth in the annexed claims.

I claim:

1. A bell of sheet material comprising a housing, a clapper having an eye at one end and an enlarged sounder at the opposite end, a unitary support for said bell housing and said clapper having a pair of resilient arms and a bell supporting loop therebetween, said housing having a sufficiently large opening in the top thereof to permit free passage of the entire clapper in engagement with said support through the top of the housing into the interior thereof to dispose the clapper within the housing, said arms bridging said opening and in resilient engagement with the top of the housing and with the bell supporting loop thereabove.

2. A bell of sheet material comprising a housing, a clapper having a completely closed eye at one end and an enlarged sounder at the opposite end, a unitary sheet metal support for said bell housing and said clapper having a pair of resilient arms and a bell supporting loop therebetween, said housing having a sufficiently large rectangular opening in the top thereof to permit passage of the entire clapper in engagement with said support through the top of the housing into the interior thereof to dispose the clapper within the housing, and said arms spanning said opening and in resilient engagement with the opposite ends thereof at the top of the housing and with the bell supporting loop thereabove.

3. A bell of sheet material comprising a housing, a clapper having a completely closed eye at one end and an enlarged sounder at the opposite end, a unitary wire support for said bell housing and said clapper having a pair of resilient arms, a bell supporting loop medially thereof and a clapper supporting hook at the end of one of said arms, said housing having a sufficiently large opening in the top thereof to permit passage of the entire clapper in engagement with said support through the top of the housing into the interior thereof, with constrictions at the opposite ends of said opening only large enough to pass the thickness of the wire support, whereby the clapper is disposed within the housing and said arms are snapped into resilient engagement with the top of the housing at said constrictions, and with the bell supporting loop thereabove.

4. The method of assembling a bell clapper, a unitary resilient support for the clapper and the bell, and a bell housing provided with a sufficiently large opening in the top thereof to pass the entire clapper from the top of the housing into the interior thereof, which comprises mounting the clapper on the support remote from the housing, dropping the clapper foremost through the opening in the top of the housing into the interior thereof, and snapping said resilient support onto the top of said bell housing at fixed points thereof.

5. A bell as set forth in claim 2 wherein one of the resilient arms is provided with an inclined slot extending from an edge thereof to an opening near the end of the arm through which the eye of the clapper is adapted to be passed for mounting on said arm, and the free end of the other arm is adapted to terminate at the inclined slot to block the return passage therethrough of the closed eye of the clapper.
